(57) **CLAIM**

The ornamental design for a faucet handle, as shown and described.

DESCRIPTION

FIG. 1 is a rear perspective view of the faucet handle showing my new design;

FIG. 2 is a front perspective view thereof;

FIG. 3 is a left side elevational view thereof;

FIG. 4 is a top plan view thereof;

FIG. 5 is a front elevational view thereof;

FIG. 6 is a rear elevational view thereof;

FIG. 7 is a right side elevational view thereof; and,

FIG. 8 is a bottom plan view thereof.

The broken line showing of the handle set screw in FIGS. 2, 3, 5 and 7, and of the fillet in FIG. 1 are for purposes of illustration only and form no part of the claimed design.
